Primary Examiner — Karen E Eldridge Powers(74) Attorney, Agent, or Firm — Sterne, Kessler, Goldstein & Fox P.L.L.C.CLAIM

The ornamental design for a type font, as shown and described.

DESCRIPTION

The file of this patent contains at least one drawing/photograph executed in color. Copies of this patent with color drawing(s)/photograph(s) will be provided by the Office upon request and payment of the necessary fee.

FIGS. 1-7 are views of a type font showing the claimed design; and,

FIGS. 8-14 are another embodiment thereof.

1 Claim, 2 Drawing Sheets
